UNITED STATES PATENT OFFICE.

ALEXANDER T. FRASER, OF BUTTE, MONTANA.

PUMP.

1,246,253.

Specification of Letters Patent. Patented Nov. 13, 1917.

Application filed October 31, 1916. Serial No. 128,728.

To all whom it may concern:

Be it known that I, ALEXANDER T. FRASER, a citizen of the United States, residing at Butte, Silverbow county, State of Montana, 5 have invented certain new and useful Improvements in Pumps, of which the following is a specification.

This invention relates to pumps and more particularly to rotary pumps of the 10 centrifugal type especially adapted to be used for pumping fluid having more or less gritty matter in suspension. The objects of the invention are to provide a pump of this type which is mounted as a unit on a 15 sub-base whereby if the inlet and outlet connections are disconnected the pump may be removed and a new one substituted; to provide a construction in which the impeller and driving means are connected to a shaft 20 and the shaft is mounted in a bearing pedestal which may be adjusted together with the shaft to properly position the impeller in the pump casing; to provide a pump casing made of hardened metal without any 25 liner; which may be easily and quickly removed in order to substitute a new casing or impeller; to provide a new and novel means for securing the casing members together; to provide a new and novel means for secur- 30 ing the flanges to the inlet and outlet conduits of the pump; to provide an efficient construction of impeller blade whereby the life of the same may be increased; and to provide a special form of sleeve to be carried by the driving shaft and interposed be- 35 tween the latter and the packing whereby wear directly on the shaft is eliminated. These and other features of the invention will be apparent from the description taken 40 in connection with the drawings, in which,

Figure 1 is a longitudinal section in elevation, taken through the entire construction;

Fig. 2 is a sectional view through one of the impeller blades and showing the form 45 of the latter;

Fig. 3 is an end elevation of the pump with a part of the casing broken away and showing the bases in cross section.

The construction comprises a sub-base 10 which is adapted to be mounted on a concrete foundation, floor or other place where the pump is to be installed. This sub-base,

because of the special construction of the pump, may be permanently installed in the position which it is to occupy. As shown 55 in Figs. 1 and 3, the sub-base is provided with a substantially vertical flange 11 adjacent its edges and the two longitudinal flanges 11 are adapted to support a base 12. As shown, this base is formed at its oppo- 60 site longitudinal edges with a downwardly projecting flange 13, which is adapted to co- operate with the two longitudinal flanges 11 of the sub-base to prevent lateral movement of the base with respect to the sub-base. 65 The base is adjustably secured to the sub- base by means of the bolts 14 which extend through slots 15 in the base and are threaded into the sub-base 10. The base 12 may be reinforced by the longitudinally extend- 70 ing ribs 16 and on its upper side carries two vertically projecting ribs 17 on which is adapted to be slidably mounted the bearing pedestal. The bottom of this pedestal con- 75 sists of a plate 18 having side flanges 19 which are adapted to take over the vertical ribs 17 and thereby guide the pedestal in its longitudinal movement. It is adjustably secured to the base 12 by means of the bolts 20 which extend through the slots 21 and 80 are threaded into the base 12. In order to provide means for easily moving the bearing pedestal relative to the base a bolt and nut construction is mounted at one end of the bearing pedestal. As shown in Fig. 1, 85 a lug 22 formed at one end of the base 12 has rotatively extending through the same a threaded bolt 23 which engages a nut member 24 depending from the correspond- 90 ing end of the bearing pedestal. Thus when the bolt 23 is turned the bearing pedestal will be moved relative to the base and may be clamped in adjusted position by means of the bolts 20. The bearing pedestal has two upright arms 25 carrying bearings 26 95 at their upper ends for the pump shaft 27. These bearings 26 are spaced apart and a driving pulley 28 may be keyed to the shaft and mounted between the bearings. At the end of the shaft opposite the pump a thrust bearing 29 may be provided and interposed between a bearing 26 and a collar 30 on the shaft. Connected to the base at the end 100 opposite the adjusting bolt 23 is a bracket 31

which supports the pump. This bracket is formed with a substantially vertically arranged disk 32 which overhangs the bases and is provided with a central bore 33. A 5 second disk 34 of smaller diameter than the disk 32 is mounted in contact with the latter and is formed with a projecting boss 35 which is seated in the bore 33 and is also formed with a central bore 36. On the opposite side of the disk 32 a bearing and stuffing box is arranged, which consists of a hollow substantially cylindrical member 37 having at one end a flange 38 which is adapted to seat against the disk 32 and a 10 boss 39 seated in the bore 33. The disks 32 and 34 and the flange 38 are all clamped together by means of a series of bolts 40. The interior of the member 37 may be formed with a flange 41, the inner surface 20 of which is adapted to bear on a hardened metal sleeve 42 mounted on the shaft 27. At its opposite end the member 37 is adapted to receive a gland 43 which may be of the usual construction and packing of any 25 desired kind may be interposed between the gland, flange 41, member 37 and the hardened metal sleeve 42. A grease ring 44 may be located adjacent the flange 41 and provided with an annular groove 45 having a 30 series of radially extending perforations 46, the member 37 being provided with an aperture 47 through which a lubricant may be injected to the grease ring.

The shaft 27 is formed with a reduced 35 threaded end 48, thereby providing a shoulder 49. The sleeve 42 is made with an inwardly projecting flange 50 at one end which is adapted to abut against the shoulder 49. The impeller of the pump consists 40 of a disk 51 having a centrally projecting hub 52, which is adapted to be mounted on the threaded end 48 of the shaft. On the opposite side of the disk 51 the impeller blades 53 are arranged. The hub 52 of the 45 impeller is screwed onto the shaft so that the flange 50 of the hardened metal sleeve 42 will be clamped between the same and the shoulder 49. The sleeve 42 is thus securely held in position and eliminates the wear 50 which would otherwise result because of the rotation of the shaft in the packing of the stuffing box.

Fig. 2 illustrates the shape of the impeller blades in cross section. As shown, the blade 55 projects substantially at right angles from the disk 51 and at its free end is formed with a flange 54. The blade and disk and the blade and flange are connected by the well rounded fillets 55. In pumping gritty 60 materials it is found that the blades are worn away very rapidly at the portion adjoining the disk. Consequently by providing fillets the life of the blades is greatly prolonged.

65 The casing which surrounds the impeller

consists of a plurality of members. The disks 32 and 34 previously described form one side of the casing. Because of the difference in diameters of these two disks, an annular seat 56 is formed and the casing 70 is adapted to be completed by a member 57 which has an edge 58 arranged in the seat 56. This casing member consists of a peripheral portion 59 which may be in the form of a volute and has a side portion arranged oppositely to the disks 32 and 34, this side portion being formed with an inlet conduit 60. The peripheral portion of the casing member may be provided with a discharge conduit 61. The impeller blades, 80 casing member 57 and, if desired, the disk 34 may be of hardened metal, the edge 58 of the casing being ground to tightly fit in the seat 56. The bosses 35 and 39 are slightly spaced apart, thereby forming a 85 chamber 62 to which water may be fed by means of the pipe 63 to provide a water-seal. The disk 32 at its outer edge is provided with a rounded flange 64 and the casing member 57 is formed with a correspondingly arranged annular recess 65. The casing member 57 is adapted to be held and clamped to the disks 32 and 34 by means of clamps which are arranged entirely exteriorly of the same. As clearly shown in 90 the drawings, these clamps 66 are formed at one end with a hook member 67, which is adapted to take over the flange 64 on the disk 32, and at their other ends with a lug 68 through which is threaded a screw 69, 100 the end of which is adapted to be seated in the recess 65. Thus it will be apparent that by operating the set screw 69 the clamp will force the casing members together and hold them in clamped position. Any desired number of these clamps may be used and because they may be spaced as desired the casing member 57 may be turned so that the discharge conduit 61 will be at any desired angle. Thus it will be apparent that a 110 casing is provided which is made of hardened metal and has no liner and can be very quickly and easily taken apart and can be adjusted for connection to a discharge pipe regardless of the angle the latter makes 115 with the pump.

Because the casing member is formed of hardened metal it is practically impossible to machine the same and for this reason a special connection must be provided in order 120 to mount the pipe flanges on the inlet and discharge conduits. As clearly shown in the drawings, this construction comprises one or more beads 70 which are formed on the exterior of the conduits. The flange 73 125 adapted to be mounted on these conduits has its bore formed with an equal number of recesses 71 corresponding to the beads 70 and the said bore is of such a diameter that the flange will just slip over the beads 70 130

when it is hot. Consequently when it has cooled the beads and recesses will coöperate to hold the flange on the conduit. However, as there will be a space between these parts 5 a filling 72 of any desired composition or alloy may be run in between the same while the flange is still hot. Thus it will be apparent that the flange is very securely mounted on the conduits. Furthermore because the 10 flanges are detachable, when the casing is worn out they may be taken off and mounted on a new casing thereby saving the cost of the same. Heretofore casings which have been constructed of hardened metal have 15 had the flanges cast integral therewith because it has been impossible to thread the inlet and outlet conduits due to the hardness of the metal.

It will be noted that because of the location of the joint between the casing members and because of the side disk 51 on the impeller said joint is subjected to very little wear as there is practically no circulation of fluid between the disk 51 of the impeller 20 and the disk 34 of the side of the casing. Furthermore, because the entire pump is mounted on a sub-base the inlet and discharge connections may be broken and the pump slid to one side on the same and any 25 desired repairs made. Then the pump may be pushed back to its former position, or the pump may be entirely removed and a duplicate one substituted. Because of the sub-base, the new pump will be in correct 30 position and alignment. It will be observed that because the impeller has a disk 51 at one side and is open at the other the wear on the casing 57 will be greatest on the left hand portion, as viewed in Fig. 1. This 35 wear may be compensated for and the impeller moved toward the left hand side of the casing by means of the adjusting screw 23. By properly turning this screw the bearing pedestal together with a shaft 27 40 and the impeller mounted thereon will be moved to carry the impeller toward the left hand side of the casing. It is obvious that 45 this adjustment may be made while the pump is running and is very easily and 50 quickly performed.

Although the flanges 73 have been described as having a bore slightly smaller than the exterior diameter of the beads 70, it is apparent that the bore might be of 55 the same diameter or slightly larger than the beads 70 as the alloy will securely hold the flanges in position. Even if the bore is of greater diameter than the beads, it is advisable to heat the flange as the alloy 60 flows in more readily, and the contraction of the flange in cooling assures a tight fit between the parts.

It is obvious that many changes may be 65 made in the structure without departing from the spirit of the invention.

Having thus described the invention, what is claimed and desired to be secured by Letters Patent is:

1. A pump construction comprising a casing, a base, a bracket carrying said casing and mounted on said base, a bearing pedestal adjustably supported on said base for movement toward and from the bracket, said pedestal having two spaced bearings, a shaft projecting into the casing carried 70 by the bearings of said pedestal and movable with the latter and having a pulley mounted between said bearings, an impeller mounted on the shaft within the casing, and means for adjusting said pedestal on 75 said base whereby the impeller may be properly positioned in the casing.

2. A pump construction comprising a sub-base, a base carried by said sub-base and having a bracket at one end, a centrifugal pump carried by said bracket, a bearing pedestal adjustably supported on said base, and a driving shaft mounted in said bearing pedestal and extending into said 80 pump.

3. In a centrifugal pump construction, a shaft having one end reduced forming a shoulder, an impeller mounted on said reduced end, a hardened metal sleeve having an inwardly projecting flange at one end thereof, said sleeve arranged on the shaft with the flange clamped between the impeller and the shoulder, and a stuffing box 95 surrounding said sleeve.

4. In a centrifugal pump construction, a 100 bracket provided with a disk, a second disk of smaller diameter attached to the first disk thereby forming an annular seat, a pump casing member of hardened metal having a rim portion one edge of which is 105 adapted to fit said annular seat, and means on the exterior of the casing for clamping the said member to the seat.

5. A centrifugal pump construction adapted to handle gritty material, comprising a 110 casing having a plurality of members of hardened metal, one of said members having a discharge conduit and radially removable means arranged entirely exteriorly of said members for holding the members together with the said conduit arranged in any desired tangential position.

6. A centrifugal pump construction adapted to handle gritty material comprising a casing having a plurality of members of 120 hardened metal, one of said members having a discharge conduit, and clamps extending around the peripheries of and engaging the two end members and adapted to secure the members together with the said 125 conduit arranged in any desired tangential position.

7. In a centrifugal pump construction, a casing of hardened metal having inlet and outlet conduits, means for securing a flange 130

4
to said conduits comprising a bead formed around said conduits, a flange formed with a corresponding recess in the bore thereof, the diameter of the bore being such as to just slip over the bead when the flange is hot, and an alloy metal filling between the bead and the bore of the flange.

5. An impeller for a centrifugal pump

adapted to pump gritty material comprising a disk having blades on one side thereof, 10 the blades being formed with flanges at their other edges and joined to the disk and flanges with well rounded fillets.

In testimony whereof I affix my signature.

ALEXANDER T. FRASER.
